INVENTOR

BY Victor J. Evans

ATTORNEY

John C. Bratton
WITNESS:

UNITED STATES PATENT OFFICE.

DANIEL V. MURTHA, OF NEW YORK, N. Y.

AUTOMATIC BRAKE.

Application filed December 13, 1924. Serial No. 755,740.

To all whom it may concern:

Be it known that I, DANIEL V. MURTHA, a citizen of the United States, residing at New York city, in the county of New York and State of New York, have invented new and useful Improvements in Automatic Brakes, of which the following is a specification.

This invention relates to improvements in automatic brakes for use in connection with dumb waiters or hand operated elevators which are commonly installed in homes and restaurants for hoisting a load from one floor to the other.

The principal object of the invention is the provision of a device which is automatically operable to prevent a load placed upon a dumb waiter from overbalancing the counterweight when the pull is released from the usual pull rope or when the counter-weight overbalances the load of the dumb waiter. The device is adapted to check the movement of the dumb waiter at any point in its path of movement.

Another object of the invention resides in an automatic brake wherein the mechanism is entirely enclosed, but in which access may be readily had should any of the parts require immediate attention.

With these and other objects in view, the invention resides in certain novel construction and combination and arrangement of parts, the essential features of which are hereinafter full described, are particularly pointed out in the appended claims, and are illustrated in the accompanying drawing, in which:

Figure 1 is a view showing my invention installed in the shaft of a dumb waiter.

Figure 2 is an enlarged elevation of my improved automatic brake.

Figure 3 is a vertical transverse sectional view on the line 3—3 of Figure 2.

Figure 4 is a transverse sectional view on the line 4—4 of Figure 3.

Figure 5 is a detail perspective view of the hoisting pulley.

Referring more particularly to the drawing, the reference numeral 10 designates a dumb waiter shaft, 11 the dumb waiter or car movable vertically within said shaft, and 12 the pulley rope which passes over a grooved pulley wheel 13 mounted in the top of the shaft 10. The numeral 14 designates a hoisting rope or cable, one end of which is fastened to the car 11 and the other end supporting a counterweight 15. The rope 14 between its connection with the car and the counterweight passes over a grooved hoisting pulley 16, both the pulleys 13 and 16 being mounted upon a horizontally disposed shaft 17, which shaft is mounted for rotation in bearings 18 adjacent the top end of the dumb waiter shaft 10. The pulley 13 is keyed to the shaft while the pulley 16 is loosely mounted thereon for a purpose to be presently described.

An annular casing 19 is cast integral with one of the bearings 18 and has one of its sides open against which the pulley wheel 16 is positioned to provide a closure for the open side of the casing. The pulley wheel 16 is held tight against the casing by a collar 20 which is fixed to the shaft 17 by a suitable set screw 21. The casing 19 is formed with an annular flange 22 which extends toward the open side of the casing and serves as a brake drum for coaction with a split brake band 23 which fits about the outer face of the same.

The ends of the brake band 23 are disposed adjacent each other and are formed with lugs 24 which extend over the edge of the flange 22 as shown in Figure 3 of the drawing. The brake band is further provided with spaced lugs 25 arranged diametrically opposed lugs 24 and which define a notch 26.

A plug or collar 27 is fixed to the shaft 17 within the confines of the flange 22 by a suitable set screw 28 and is formed with an outwardly extending segment 29 which extends slightly less than half the distance about the shaft 17. A shoe or plate 30 is

arranged over the segment 29 and is formed with an arm 31 which is seated in the notch 26 of the brake band between the lugs 25. Diametrically opposite the arm 31, the plate 5 is formed with a pair of jaws 32 for co-action with the curved faces of the lugs 24 on the free ends of the brake band 23. The central portion of the plate is cut-away to receive the segment 29 and is formed with 10 shoulders 33 for engagement with the ends of the segment when the device is in operation. The plate is further provided with shoulders 34 disposed on opposite sides of the arm 31.

15 One side of the pulley wheel 16 is formed with spaced lugs 34 which extend into the casing and straddle the arm 31 of the plate 30 for co-action with the shoulders 34 during the operation of the braking mechanism.

20 In operation, the rope 12 is pulled in either direction depending on whether it is desired to move the dumb waiter up or down the shaft which rotates the wheel 13 and in turn imparts a rotary movement to the shaft 17.

25 As the shaft rotates the end of the segment 29 engages one of the shoulders 33 in the plate depending on the direction of rotation of the shaft which causes the plate and brake band 23 to also rotate and which plate 30 imparts a rotary movement to the hoisting wheel 16 by reason of the lugs 34 contacting with the shoulders 34'. It will therefore be seen that the hoisting pulley wheel will rotate when the pulley 13 is rotated by reason 35 of the rope 12 and will cause the hoisting rope to lift or lower the car as the occasion demands.

We shall now presume that a load is placed upon the car and which is of a greater or 40 less weight than the counterweight, and the pulley rope is left free. The weight of such load will in the event that the load overbalances the counterweight, or if the counterweight overbalances the load, rotate the pulley 16 causing one of the lugs 34 to engage one of the shoulders 34' of the plate 45 causing the plate to move whereby the jaws 32 set up a wedging action with the lugs 24 on the end of the brake band thereby causing 50 the brake band to be contracted about the flange or drum 22 of the casing and which casing is rigidly secured to the supporting structure. It will now be seen that the greater the force applied to the wheel 16 to rotate 55 the same the greater will be the braking action between the brake band and the drum. When the pressure is relieved from the pulley, the brake band will automatically expand thereby breaking its grip on the drum 60 due to the normal tendency of the band to expand.

From the foregoing description, it will be seen that I have provided a brake which is automatic in its action for supporting a 65 car in various planes of elevation and where-

in the mechanism for performing this function is exceedingly simple and is enclosed in a novel and attractive manner.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims. 70 75

What is claimed as new is:—

1. In a device of the class described, the combination with a stationary casing, a rotatable shaft having one of its bearings therein, an annular drum arranged within said casing, a split band encircling said drum and normally free to rotate about said drum, a collar fixed to said shaft, a pulley wheel loosely mounted on said shaft, and means between said collar and said pulley wheel for causing said band and pulley wheel to move with said shaft upon rotation of the same, said means including a member having shoulders for co-action with lugs extending from said pulley wheel. 80 85 90

2. In a device of the class described, the combination with a stationary casing, a rotatable shaft extending therethrough, an annular drum arranged within said casing, a split band encircling said drum and normally free to rotate about said drum, a collar keyed to said shaft, a pulley wheel loosely mounted on said shaft, and means between said collar and said pulley wheel for causing said band and pulley wheel to move with said shaft upon rotation of the same, and means automatically operable upon the rotation of said pulley wheel independent of 105 said shaft for moving said split band into frictional binding action with said drum to lock said pulley wheel against rotation in either direction. 95 110

3. In a device of the class described, the combination of a stationary casing, a rotatable shaft having one of its bearings therein, an annular drum formed on the side wall of said casing within the same, a split resilient band encircling said drum, a collar fixed to said shaft, a member, jaws on said member for co-action with the free ends of said split band, shoulders on said member for co-action with a portion of said collar upon the rotation of said shaft, a pulley wheel loosely mounted on said shaft, and means on said pulley wheel for co-action with said member for moving said member to cause said jaws to compress the free ends of said split band to contract said band about said drum 120 upon the movement of said pulley wheel independent of said shaft. 115 125

4. In a device of the class described, the combination of a stationary casing open at one side, a rotatable shaft having one of its 130

- bearings therein, an annular drum formed on the side wall of said casing within the same, a split resilient band encircling said drum, a collar fixed to said shaft, a member, 5 jaws on said member for co-action with the free ends of said split band, shoulders on said member for co-action with a portion of said collar upon the rotation of said shaft, a pulley wheel loosely mounted on said shaft 10 and disposed against the open side of said
- casing to close the same, and means on said pulley wheel for co-action with said member for moving said member to cause said jaws to compress the free ends of said split band to contract said band about said drum upon the movement of said pulley wheel independent of said shaft. 15

In testimony whereof I have affixed my signature.

DANIEL V. MURTHA.
